UNITED STATES PATENT OFFICE.

WILLIAM H. MULLINS, OF SALEM, OHIO.

DESIGN FOR A PLEASURE-BOAT.

SPECIFICATION forming part of Design No. 25,159, dated February 11, 1896.

Application filed January 6, 1895. Serial No. 574,555. Term of patent 31 years.

To all whom it may concern:

Be it known that I, WILLIAM H. MULLINS, a citizen of the United States, residing at Salem, in the county of Columbiana and State of Ohio, have invented and produced a new and original Design for Pleasure-Boats, of which the following is a description, due reference being had to the accompanying drawings, wherein—

10 Figure 1 is a perspective view, and Fig. 2 a top plan view, of my invention.

The general purpose of this invention is the construction and ornamentation of a boat upon lines especially graceful and aesthetic in appearance, having for its leading features a double-ended clinker-built or lap-streak boat A, the gunwales of which at their upper edges are encompassed by a rope-molding B, and both sides of which at the bow and stern are embellished by a conventional scroll C C of gradually-diminishing pattern, trending from the extremities of the boat in a midship direction. At points immediately above the side scrolls C C the gunwales are connected by duplicate half-decks D D, forming top closures or covers for air-tight compartments E E, as shown, each ornamented upon the upper surface by a cluster of rushes and reeds F F crossing said decks in a longitudinal direction, and having their lower ends hidden from view by ornamental figure-heads. These figure-heads G G, which surmount the structure at its extremities, consist in representations of an eagle's head and neck oppositely disposed upon the decks aforesaid, from which they rise with slightly-overhanging beaks H H, in each of which is secured a ring I I.

The interior of the boat is crossed transversely by seats J extending from gunwale to gunwale, the latter at suitable points being surmounted by oar-locks K, completing the design.

What I claim is—

The design for a pleasure-boat, substantially as herein shown and described.

In testimony whereof I subscribe my signature in presence of two witnesses.

WILLIAM H. MULLINS.
